TENT

Davie W. Norvell, Greensboro, N. C.

Application April 30, 1935, Serial No. 19,082

1 Claim. (Cl. 135—4)

This invention relates to tents, and it is primarily an object of the invention to provide a structure of this kind which can be readily and conveniently erected by a single person and which 5 comprises in its structure a sectional frame collapsible to occupy a minimum of space when not in use.

It is also an object of the invention to provide a structure of this kind which can be readily 10 and conveniently transported from one location to another whereby it is particularly desirable for use as a grave tent.

Another object of the invention is to provide 15 a device of this kind including a sectional supporting frame, said sections being readily interchangeable.

A further object of the invention is to provide 20 a tent of this kind which is free of any interior obstruction, such as a center pole and wherein the assembled structure provides a tent which will be staunch and steady.

The invention consists in the details of construction and in the combination and arrangement 25 of the several parts of my improved tent whereby certain important advantages are attained and the device rendered simpler, less expensive and otherwise more convenient and advantageous for use, as will be hereinafter more fully set forth.

30 The novel features of my invention will hereinafter be definitely claimed.

In order that my invention may be the better understood, I will now proceed to describe the same with reference to the accompanying drawings, wherein:—

Figure 1 is a view in perspective of a tent structure embodying my invention, the canopy being omitted but a side wall being in place;

Figure 2 is a view in perspective with the 40 canopy or tent top applied and also showing a second side wall guyed up;

Figure 3 is a fragmentary view in perspective from within of the tent top showing a means for attaching the same to the frame;

45 Figure 4 is a fragmentary view partly in section and partly in elevation illustrating the lower portion of a corner post and the anchoring stake associated therewith;

Figure 5 is a view in top plan of the frame 50 structure as herein disclosed;

Figure 6 is an enlarged fragmentary detailed view partly in section and partly in elevation of the upper portion of a corner post and the parts directly associated therewith;

55 Figure 7 is an elevational view of the crown

member of the frame and certain of the parts directly engaged therewith;

Figure 8 is a fragmentary view partly in section and partly in elevation showing the connection between the sections of a top bar. 5

As disclosed in the accompanying drawings, my improved tent comprises a frame structure F. This frame structure has the four corner posts 1, the lower end portion of each of which being tubular and open at the end of the post. The opposite end portion of each of the posts 1 has engaged therover and secured thereto a cap 2 and extending outwardly from said cap 2 at the axial center of the post is a pin 3 rigid with the cap. The cap 2 has radiating therefrom and also with 10 respect to the pin 3 the perpendicularly related lugs 4 and midway between such lugs 4 and also radiating from the cap 2 and the pin 3 thereof is a third lug 5.

Straddling each of the lugs 4 is a bifurcated 20 head 6 carried by an end of a side bar 7 and said head 6 is pivotally secured, as at 8, to its lug 4. The various side bars 7 are of the same length so that in its assembly the tent is square in top plan. This is of advantage as it does not require any 25 predetermined arrangement of the corner posts but that they can be interchangeably used to the same advantage.

Each corner post 2 as is believed to be clearly understood, carries two side bars 7 and the outer end portion of one of the bars is tubular, as at 10 in Figure 1, while the outer end portion of the second side bar 7 carries a reduced extension 11 which is adapted to be snugly and telescopically received within the tubular portion 10 of a bar 7 of another section of the frame. When the extension 11 is engaged within the telescopic portion 10 the two bars 7 are coupled together by a cotter pin 12 or the like readily insertable through suitably provided openings in the extension 11 and the walls of the tubular portion 10 into which said extension 11 is received. To prevent loss of this pin 12 the same is anchored to a bar 7 in a conventional manner through the medium of a chain 14 or other desired flexible member of sufficient length. 30 35 40 45

When the frame is disassembled the bar 7 of each section or unit will swing to a position alongside of the associated corner post 1 so that said section or unit will occupy a minimum of 50 space and can be readily transported from one location to another as may be desired.

The tent top or canopy T is cut to the required size with the sections assembled to assure the desired pitch of such top or canopy when applied. 55

The corners of the top or canopy T are reinforced, as at 15, and each of said reinforced portions is provided with an opening whereby said corner portion may be detachably engaged over 5 an outstanding pin 3 of a corner post 1.

In setting up the tent four suitably positioned stakes 16 are driven into the ground with a sufficient portion of said stake extending above the ground level. To assure this extension above the 10 ground I find it of advantage to provide the stake at a desired point intermediate its ends with a collar 17 which serves as a stop to limit the extent of penetration of the stake into the ground.

The lower tubular end portion of a corner post 15 1 is then engaged over the upstanding portion of a stake 16 whereby said post is effectively maintained in desired vertical position. The side bars 7 of one post are then swung upwardly and coupled to the side bars 7 of the adjacent corner 20 post in the manner as has hereinbefore been referred to. After this has been done the tent top or canopy T is then operatively connected at its corner portions with the pins 3 of the corner posts 1. When this has been done the rafter structure 25 R is applied. This rafter structure comprises a center head or crown member 18 which carries four lugs 19 radiating from the axial center of the head or crown member 18. These lugs are also equidistantly spaced around 30 the member and each of said lugs 19 is straddled by a bifurcated head 20 carried by an end of an elongated rafter member 21. This head 20 is pivotally connected, as at 22, to the lug 19. The opposite end portion of the rafter member 21 is 35 also provided with a bifurcated head 23 which is adapted to straddle a lug 5 and be detachably locked to such lug 5 by a cotter pin 24. This cotter pin 24 is carried by a chain or other flexible member 25 of desired length and which chain is 40 suitably secured to the adjacent corner post 1 whereby the pin 24 is held against loss.

Each of the cotter pins 24 can be readily removed or applied and such application or removal is facilitated by having the lugs 5 below 45 the lugs 4 or more particularly to have the pivotal connections as afforded by the pins 24 a sufficient distance below the pivotal connections 8 to allow ready access to the pins 24 by a person within the tent when setting up the structure.

The head or crown member 18 at its axial 50 center is provided with an extended pin 26 and in applying the rafter structure this pin 26 is inserted from below through a suitably positioned opening provided in the central reinforced portion 27 of the tent top or canopy T and the operator then forces up the member 18 by each of the arms 21.

The arms 21 of course are handled in turn and after each arm 21 has been moved upwardly to 60 its limit its bifurcated end 23 is secured to a lug 5 and after all four of the arms have been so manipulated the tent top or canopy T is effectively raised and held in working position. Although not illustrated in the accompanying drawings, when desired suitable guy ropes may be engaged 65 with the corner pins 3 and secured in the regular way to suitably positioned stakes.

The marginal portions of the tent top or canopy T as herein disclosed is each defined by an apron 28 and extending along the junction between each of the aprons 28 and the tent top or canopy T from within is a reinforcing strip 29. This strip 29 at desired points therealong has se-

cured thereto buckle straps 30 whereby the marginal portion of the tent top or canopy T between adjacent corner posts 1 may be tied or secured to the adjacent side bars 7 and thus further hold the tent top or canopy T in position. 5

The sides of the tent structure may be closed by side curtains and in Figure 1 is illustrated one of said curtains C in position. The upper and side marginal portions of this curtain carry buckle straps 31 for engagement with the adjacent corner posts 1 and the associated side bars 7 for holding said side curtain in position. As disclosed in Figure 1, the curtain C in its upper corners is provided with the flaps 32 which are engaged with the pins 3 of the corner posts. 15

In Figure 2 of the drawings I show a second applied side curtain C guyed up to serve either after the fashion of an awning or to increase the capacity of the tent. By having guyed up curtains at all four sides of the tent structure it will be obvious that the capacity of the tent will be materially increased. 20

The arms 21 as herein disclosed are each preferably sectional so that they can be knocked down for convenience in transportation. As 25 particularly illustrated in Figure 8 the section of one arm 21 has a reduced extension 33 which is snugly and telescopically received within the hollow end portion of the adjacent section and co-acting with said telescopically engaged parts is a 30 holding bolt 34.

The particular manner of attaching the bars 7 to the corner posts 1 and the rafter members 21 to the corner posts 1 and to the head or crown member 18, is such as to permit the frame to be 35 effectively employed on an uneven surface such as is to be expected in a cemetery. This particular assembly readily permits of a material up and down variation of the corner posts 1 one independently of the other and also a lateral 40 swinging movement of the corner posts 1.

From the foregoing description it is thought to be obvious that a tent constructed in accordance with my invention is particularly well adapted for use by reason of the convenience 45 and facility with which it may be assembled and operated, and it will also be obvious that my invention is susceptible of some change and modification without departing from the principles and spirit thereof and for this reason I do not 50 wish to be understood as limiting myself to the precise arrangement and formation of the several parts herein shown in carrying out my invention in practice except as hereinafter claimed.

I claim:—

A supporting frame for a tent having a pyramid roof comprising corner posts, a side arm interposed between each pair of adjacent corner posts, means for pivotally connecting the extremities of the side arms to the upper end portions 60 of the corner posts, a crown member, rafter arms, means for pivotally connecting the upper end portions of the rafter arms to the crown member, and means for detachably and pivotally connecting the lower end portion of each rafter arm to a corner post at a point below the pivotal connections of the side arms with said post, the pivotal connections for the side arms and rafter arms permitting independent up and down movement 65 of each of the corner posts and also a lateral 70 swinging movement of the corner posts. 70

DAVIE W. NORVELL.
